UNITED STATES PATENT OFFICE.

MARTIN F. McCARTHY, OF DAVENPORT, IOWA.

EXPANSION-JOINT FOR CONCRETE PAVEMENTS.

1,033,431.

Specification of Letters Patent.

Patented July 23, 1912.

Application filed February 2, 1912. Serial No. 674,957.

To all whom it may concern:

Be it known that I, MARTIN F. McCARTHY, a citizen of the United States, and a resident of Davenport, in the county of Scott and State of Iowa, have invented certain new and useful Improvements in Expansion-Joints for Concrete Pavements, of which the following is a specification.

My invention relates to the art of laying concrete pavements, and has for its object the provision of an improved means for allowing for the expansion and contraction of the pavements, and consists of the provision of a strip of sheet metal bent into a U shape in cross-section and its edges formed with lateral flanges having lugs or projections that engage the concrete to hold the flanges in engagement with the pavement on the two sides of the joint.

My invention will be described in detail hereinafter, and illustrated in the accompanying drawings, in which—

Figure 1 is a top plan view of a fragment of a concrete pavement showing my improved joint in position; Fig. 2, a cross-section of the pavement and joint; and Fig. 3, a view in side elevation of my improved joint.

In the drawings similar reference characters will be used to designate corresponding parts in the several views.

A A indicate the strips of pavement on the two sides of my improved joint that consists of a strip of sheet-metal 1, bent into a U shape, as shown, and when in position, as shown in Figs. 1 and 2, the two sides of the U-shaped portion, designated 2, engage the adjacent edges of the pavement.

3 3 indicate flanges extending laterally from the upper edges of the sides 2, and are adapted to seat on the top of the concrete adjacent to the joint and to be pressed therein while the concrete is still soft, so that the upper surface of the flanges are on the same plane as the upper surfaces of the sec-

tions of pavement on the two sides of the joint.

4 indicates downwardly-extending lugs or projections formed integral with the flanges 3 by cutting out portions of the metal of the sheet of metal and turning the prongs formed thereby downwardly, or the lugs or projections may be secured to the flanges, if desired, said lugs or projections by being pressed into the concrete before it hardens 55 operate to hold the joint member in position, as shown and stated. After the joint is completed the space between the sides 2 of the U-shaped portion may be filled with pitch or asphaltum, indicated at 5, to provide for 60 expansion and contraction of the pavement.

When in use it will be apparent that the flanges 3 will protect the edges of the pavement abutting the U-shaped portion and prevent it from chipping or breaking, and the 65 U-shaped portion will open and close when the pavement contracts or expands because of changes of temperature, the pitch or asphaltum filling the space between the sides 2 when the joint member opens because of 70 contraction of the pavement, but because of its viscosity permitting the pavement to expand without endangering its integrity.

Having thus described my invention, what I claim is—

A joint member for concrete pavements comprising a strip of sheet-metal bent in a U shape in cross-section, laterally-extending flanges on the upper edges of said U-shaped portion, and downwardly-extending anchoring lugs or projections on said flanges, substantially as shown and described.

In witness whereof, I have hereunto set my hand in presence of two subscribing witnesses.

MARTIN F. McCARTHY.
